UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

GUN-MOUNTING.

1,318,056.

Specification of Letters Patent.

Patented Oct. 7, 1919.

Application filed June 26, 1919. Serial No. 306,957.

To all whom it may concern:

Be it known that we, Sir ARTHUR TREVOR DAWSON, knight, and Sir GEORGE THOMAS BUCKHAM, knight, both subjects of the King of Great Britain, residing at Vickers House, Broadway, Westminster, in the county of London, England, have invented certain new and useful Improvements in or Relating to Gun-Mountings, of which the following is a specification.

This invention relates to a leveling device for use with a gun mounting carried by a movable structure, this device being for the purpose of enabling the training axis to be brought into and maintained in a position in which it is truly vertical. The invention is particularly but not exclusively applicable to mobile anti-aircraft gun mountings carried by trolleys or trucks; it is also applicable to naval gun mountings and in this case the leveling device may be used for the purpose of compensating for the rolling movements and the pitching and tossing movements of the ship.

According to the invention the improved leveling device is made independent of the parts of the gun carriage and mounting and comprises two superposed members or castings the upper one of which is adapted to receive the gun mounting and is capable of sliding on a curved bearing surface on the other or lower member and the latter is capable of sliding on a curved bearing surface on a seating on the trolley or other movable structure for transporting the mounting, these curved surfaces being situated in planes at right angles to each other so that leveling adjustments of the gun mounting can be effected in any direction. The said bearing surfaces are preferably part-cylindrical and of large radius and suitable clips may be provided for maintaining the members in contact with the said bearing surfaces.

In order that the said invention may be clearly understood and readily carried into effect the same will now be described more fully with reference to the accompanying drawings, in which:—

Figure 1 is a sectional side elevation of a gun mounting supported on a caterpillar;

Figs. 2 and 3 are respectively a side elevation and an end elevation of the leveling device drawn to an enlarged scale, and

Figs. 4 and 5 are sections taken approximately on the lines 4, 4 and 5, 5 of Figs. 3 and 2 respectively.

A, B are respectively the upper and the lower members or castings of the leveling device, the former having a flat upper portion *a* to which the base of the gun mounting *A'* is bolted and part cylindrical lower surfaces *a'*, *a'* adapted to slide on corresponding curved bearing surfaces *b'*, *b'* on the upper part of the lower casting B; the latter is formed on its lower part with part cylindrical surfaces *b*, *b* adapted to slide on correspondingly curved bearing surfaces *c*, *c* on a seating C rigidly attached to the gun trolley or other movable structure parts of which are indicated by C'. The surfaces *a'*, *b'* are disposed at right angles to the surfaces *b*, *c*.

The means for effecting the adjustments of the castings A and B comprise (see Figs. 2 to 5) two worms *A'* and *B'* of which the worm *A'* is carried by the lower casting B and meshes with a worm-wheel segment *A*² on the upper casting A, and the worm *B'* is carried by the seating C and meshes with a worm-wheel segment *B*² on the lower casting B. It will be observed that the two sets of worm gearing are disposed centrally beneath their respective castings and that the aforesaid bearing surfaces are arranged in duplicate on each side of the gearing. The worm gearing is made capable of being readily removed for replacement or repair, for which purpose the worms are connected to their shafts *A*³, *B*³ by splines as shown so that the worms can be disconnected therefrom by withdrawing the shafts axially, thereby enabling the lower worm *B'* to pass through a hole *C*² in the seating C normally covered by a detachable dust guard *c*². The worm-wheel segments are detachably connected by bolts or otherwise to the castings carrying them, the lower segment *B*² when

in position covering a slot b^2 in the lower casting B; by removing this segment through the aforesaid hole C² the slot b^2 is uncovered to enable the upper worm A' to 5 pass through the slot and the hole and access can then be had to the upper worm-wheel segment A² which, when detached, can be removed by passing it through the slot and the hole.

- 10 The worm shaft A³ is in Figs. 2 to 5 operated by handles a^3 , a^8 either directly or through a ratchet contrivance as shown and the worm shaft B³ is similarly operated. In Fig. 1 the worm shaft A³ (not shown) is 15 connected at its ends through bevel gearing to two vertical shafts A^{3x}, A^{3x} to the squared end of either of which, as may be found convenient, the stem of a hand-wheel a^{3x} can be connected; the worm shaft B³ (not 20 shown) is similarly connected to a vertical shaft B^{3x} having a squared end to enable the stem of a hand-wheel to be connected. Spirit levels or other level indicating 25 devices may be provided on the upper casting and suitable clips a^x , b^x attached to or made integral with the castings are provided for maintaining the upper casting in contact with the bearing surfaces on the lower casting and the latter in contact with the bearing 30 surfaces on the seating.

Instead of the worm gearing above described screw threaded shafts and nuts may be employed.

What we claim and desire to secure by 35 Letters Patent of the United States is:—

1. The combination with a movable structure for transporting a gun mounting, of a leveling device which is made independent of the gun carriage and mounting and comprises two superposed members of which 40 the upper one receives the gun mounting and is slidably mounted on a curved bearing surface on the other or lower member and the latter is slidably mounted on a second curved 45 bearing surface, these bearing surfaces being so situated that the movements of the two members occur in planes at right angles to each other.

2. The combination with a movable structure for transporting a gun mounting, of a leveling device which is made independent of the gun carriage and mounting and comprises two superposed members of which the upper one receives the gun mounting and is 55 slidably mounted on a part-cylindrical bearing surface of large radius on the other or lower member and the latter is slidably mounted on a second part-cylindrical bearing surface of large radius, these bearing 60 surfaces being so situated that the movements of the two members occur in planes at right angles to each other.

3. The combination with a movable structure for transporting a gun mounting, of a 65 leveling device which is made independent

of the gun carriage and mounting and comprises two superposed members of which the upper one receives the gun mounting and is slidably mounted on a curved bearing surface on the other or lower member and the latter is slidably mounted on a second curved bearing surface, these bearing surfaces being so situated that the movements of the two members occur in planes at right angles to each other, and clips for maintaining each member in contact with its bearing surface. 70

4. The combination with a movable structure for transporting a gun mounting, of a leveling device which is made independent of the gun carriage and mounting and comprises two superposed members of which the upper one receives the gun mounting and is slidably mounted on a part-cylindrical bearing surface of large radius on the other or lower member and the latter is slidably mounted on a second part-cylindrical bearing surface of large radius, these bearing surfaces being so situated that the movements of the two members occur in planes at right angles to each other, and clips for maintaining each member in contact with its bearing surface. 80

5. The combination with a movable structure for transporting a gun mounting, of a leveling device which is made independent of the gun carriage and mounting and comprises two superposed members of which the upper one receives the gun mounting and is slidably mounted on a curved bearing surface on the other or lower member and the latter is slidably mounted on a second curved bearing surface, these bearing surfaces being so situated that the movements of the two members occur in planes at right angles to each other, and clips for maintaining each member in contact with its bearing surface. 90

6. The combination with a movable structure for transporting a gun mounting, of a leveling device which is made independent of the gun carriage and mounting and comprises two superposed members of which the upper one receives the gun mounting and is slidably mounted on a curved bearing surface on the other or lower member and the latter is slidably mounted on a second curved bearing surface, these bearing surfaces being so situated that the movements of the two members occur in planes at right angles to each other, a worm wheel segment detachably connected to the upper member, a worm meshing with said segment, a shaft which is slidably connected to the worm and is carried by the lower member, a worm wheel segment detachably connected to said lower member to cover a slot therein, a seating which is attached to the movable structure and is formed with the curved bearing surface for the lower member, a worm meshing with the last mentioned segment, a shaft which is slidably connected to the last men- 115

tioned worm and is carried by said seating, the last mentioned worm when disconnected from its shaft and the last mentioned segment when disconnected from the lower member being removable through a hole in the seating and the first mentioned worm when detached from its shaft and the first mentioned segment when detached from the

upper member being removable through the slot in the lower member and the hole in the seating. 10

In testimony whereof we affix our signatures.

ARTHUR TREVOR DAWSON.
GEORGE THOMAS BUCKHAM.
